(57) **CLAIM**

The ornamental design for a portable baby bassinet, as shown and described.

DESCRIPTION

FIG. 1 is a perspective view of a portable baby bassinet showing my new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is a rear, left, bottom perspective view thereof.

FIG. 9 is an enlarged detail view of area 9 shown in FIG. 1.

FIG. 10 is an enlarged detail view of area 10 shown in FIG. 2.

FIG. 11 is an enlarged detail view of area 11 shown in FIG. 4; and,

FIG. 12 is an enlarged detail view of area 12 shown in FIG. 8.

The broken lines in the drawings depict portions of the portable baby bassinet that form no part of the claimed design.

1 Claim, 12 Drawing Sheets
